UNITED STATES PATENT OFFICE.

JOHN DOUGLAS BARTER, OF CALGARY, ALBERTA, CANADA.

ENGINE.

1,150,734.

Specification of Letters Patent. Patented Aug. 17, 1915.

Application filed December 14, 1912. Serial No. 736,714.

To all whom it may concern:

Be it known that I, JOHN D. BARTER, citizen of Alberta, Canada, and residing in the city of Calgary, Canada, have invented 5 a new and Improved Engine, of which the following is a full, clear, and exact description.

This invention relates to that class of engines in which a multiplicity of cylinders 0 are connected to a single crank casing and adapted to rotate around the center of such casing.

Among the objects of the invention is to provide an engine of the character indicated 15 which will be compact and adapted especially for aeronautical operations, the number of parts being comparatively small and the weight being small in comparison with its power.

20 Another object of the invention is to provide a construction including one or more crank disks journaled for rotation in a fixed support on an axis eccentric to the axis of rotation of the main engine system including 25 a casing, means being provided to couple the disk and casing together for simultaneous rotation at the same angular velocity, and means also being provided to cause a bodily displacement relatively between the 30 casing and disk during such rotation.

Another object of the invention is to improve this class of engines with respect to the admission of explosive mixtures and the exhaust of the burned gases.

35 A still further object of the invention is to utilize to the highest advantage the operation of the two-cycle engine.

The foregoing and other objects of the invention will hereinafter be fully described 40 and claimed and illustrated in the drawings accompanying this specification in which like characters of reference indicate corresponding parts in all the views, and in which—

45 Figure 1 is a vertical sectional view of the engine substantially on the line 1—1 of Fig. 3; Fig. 2 is a transverse sectional detail on the line 2—2 of Fig. 1; Fig. 3 is a vertical section, at right angles to Fig. 1, taken 50 on the line 3—3 of Fig. 1; Fig. 4 is a fragmentary detail of the casing and one of the disks taken on the line 4—4 of Fig. 3; Fig. 5 is a plan view of a piston and associated parts; and Fig. 6 is a detail view corre-

sponding to the section of Fig. 3, certain 55 movable parts, however, being in different positions from those of Fig. 3.

Referring particularly to the drawings, I show at 10 what may be considered as a stationary support having a circular periphery 60 and around which the casing 11 of the engine is adapted to rotate concentrically. The joint between said support and the casing is preferably packed at 11^a to make it oil tight. On the opposite side of the casing 65 and extending outwardly therefrom is a shaft 12, journaled concentrically with the support 10 in a bearing 13. The shaft 12 may be considered for the purpose of the present description as the driven or power 70 shaft.

14 and 14' represent a pair of disks arranged parallel to each other and anchored together for conjoint operation by means of any suitable number of cross bars 15. Said 75 disks are provided with gudgeons 16 and 16' journaled co-axially with each other in the aforesaid support 10 and a floating disk 10', respectively. The floating disk 10' may be regarded in effect as an extension of said 80 support 10, though separate therefrom physically, and loosely journaled in the inner face of the casing plate 11'. The axis of the disks will, therefore, be understood to be eccentric to the axis of the support 10 85 and shaft 12, and so far as now described said disks are free to rotate around their said axis. The engine casing 11 and the disks are coupled together by means of a plurality of links 17, each of which is pivotally connected at one end on a stud 18 carried by the casing and at the other end on a stud 19 carried by one of the disks. The effective length of said links 17 or the 90 distance between the centers of the studs 18 and 19 is equal to the eccentricity of the disks or the distance between their axis and that of the casing. It will be understood, therefore, that the casing and disks will 95 rotate simultaneously and at the same angular velocity, though on different axes.

As shown in the drawings I provide a series of cylinders 20, each provided with a piston 21 and piston rod 22. The piston rod is rigidly fixed to the piston and reciprocates through a gland 23 at the inner end of the cylinder. All of the piston rods are connected to the disks through a series of links 105

24, each link being pivoted at one end at 25 to the inner end of a piston rod and at its other end to a stud 26 carried by one of the disks. The links 24 are all equal in length 5 to the links 17 and the aforesaid eccentricity.

Referring to Fig. 1 the lowermost cylinder 20 may be regarded as being charged with compressed gases ready for an ignition. As soon as this cylinder passes from the position indicated, or with the point 25 just over the dead center, said gases will be ignited by means of the spark plug 27, the force of the explosion tending to drive the piston inward as indicated in the cylinder next ahead of 10 the one under consideration. Said force of the explosion acting through the piston rod will tend to rotate the link 24 around the center of the stud 26, and by virtue of said eccentricity said force will tend to rotate 15 the entire system of cylinders and casing, and hence the power shaft 12 connected to the casing. Considering the direction of rotation as indicated by the large arrow on Fig. 1, the pistons at the right will be understood to be acting inwardly under the force 20 of the explosions in the several cylinders, and the piston at the top of the figure will be understood to have reached the end of its inner stroke. The pistons at the left will be 25 understood as being moved outwardly, causing fresh gases to be introduced into the cylinders through the valves 28.

The means I employ for introducing explosive mixtures to the several cylinders 30 comprises a port 29 extending through the support 10 and having communication at 29' with a chamber 30 having connection through a transverse passage 30', as shown in Fig. 2, to a valve 28 through which said 35 mixture may be admitted into the bottom of the respective cylinder. It will, of course, be understood that the several chambers 30 will be brought into register successively with the port 29' at the time the pistons will 40 operate to cause the fresh gases to be admitted. The valves 28 will, of course, be held seated at other times as usual in this 45 type of engines.

Each piston on its outward stroke will 50 therefore serve, in connection with introducing a fresh charge, to place the previously admitted charge under compression on the outside of the piston or adjacent the spark plug 27. The force of the explosion, as 55 above intimated, will drive the piston inward, and when the piston reaches the point indicated in Fig. 6 the fresh mixture will be compressed sufficiently to cause the unseating of the valve 31 which will admit the 60 fresh charge through the piston, such fresh charge serving in part to purge the burned gases from the last previous explosion out of the cylinder, the bulk of such fresh mixture being retained in the cylinder above the piston 65 ready to be compressed for the next suc-

ceeding explosion, as is usual in engines of the two-cycle type.

The exhaust valve mechanism which I employ comprises an auxiliary cylinder 32 connected to each engine cylinder 20 and 70 provided with a piston 33 operating therein against the tension of a spring 34 surrounding a post 35, the head of which post is adapted to abut against one end of the piston 33 and limit the movement of the piston 75 in one direction, as shown in Fig. 3, which shows the normal position of the piston 33 maintaining the exhaust port 36 closed. The auxiliary cylinder 32 has communication with the cylinder 20 through several 80 ports, the ports 37 and 38 communicating with the inner and outer ends respectively of the cylinder 32. The inner end of the port 38 communicates with the cylinder 20 in the same transverse plane as a port 39 85 which, when the piston 33 is in abnormal position, communicates directly with the exhaust port 36 as shown in Fig. 6. When the piston is operating inwardly under the force of the explosion, the piston 33 will remain 90 in its normal position and will so remain until the inner end of the port 38 is passed or uncovered by the piston 21 and the outer end of the piston 33 will be subjected to the superior force of the exploded gases acting 95 thereon through said port 38, causing the piston 33 to move inwardly against the tension of the spring 34. In this abnormal position of the piston 33 the exhaust port 39 will be open and in communication with the 100 port 36, permitting a quick exhaust of the burned gases. As soon as the pressures are equalized on the opposite sides of the piston 21, the piston 33 will be restored to its normal position by virtue of the spring 34 and 105 the fact of the balancing forces through the ports 37 and 38.

It is to be understood that the pressure of the burned gases on the piston 21 is greater than that of the fresh charge being 110 compressed in the inner end of the cylinder, until the piston 21 uncovers the inner end of the port 38. Then the force of the exploded gases will move the piston 33 inwardly against the tension of its spring to 115 open the exhaust port 39 and permit a quick exhaust of the burned gases. When this takes place the pressure of the compressed charge will be sufficient to open the valve 31 to admit the compressed charge to the 120 cylinder.

The several parts of this engine may be made of any suitable materials and the relative sizes and proportions and also the several details of construction may be varied 125 in many particulars without departing from the spirit of the invention. I wish, therefore, not to be limited in the matters specifically illustrated except as may be required by the state of the art. 130

Having thus described my invention, what I claim as new and desire to secure by Letters Patent is:—

1. In an engine, the combination of a support, a crank casing rotatable concentrically around said support, a plurality of cylinders connected rigidly with said casing, each of said cylinders being provided with a piston and a piston rod movable radially in said casing, a disk journaled in said support for rotation on an axis eccentric to the axis of the casing, links coupling the casing and disk together for simultaneous rotation, and links equal in length to the first mentioned links and connecting said piston rods to said disk.
  2. In an engine, the combination of a support, a casing mounted on said support and rotatable therearound concentrically, a disk journaled in said support on an axis eccentric to the aforesaid axis of rotation of the casing, a series of cylinders fixed to said casing and rotatable therewith around the axis of the support, a series of pistons and piston rods operably associated with said cylinders, the piston rods being rigidly connected with said pistons, link connections between the piston rods and said disk, and means to admit explosive mixtures into the respective cylinders including a port through said support.
  3. In an engine, the combination of a support and a bearing in axial alinement therewith, a casing mounted on said support and journaled for rotation therearound, a shaft connected to said casing and extending out-
- wardly therefrom in said bearing, a pair of disks journaled for rotation on an axis eccentric to the axis of said support and shaft, links coupling the casing and disks together for simultaneous rotation, a series of engine cylinders connected to said casing, a series of pistons in the respective cylinders, a series of corresponding piston rods and links equal in length to the first mentioned links and connecting the piston rods to said disks, substantially as set forth.
4. In an engine, the combination of a support, a casing mounted on said support and adapted to rotate concentrically therearound, a series of cylinders rigidly connected to said casing, means to admit fresh mixtures to the respective cylinders, including a port leading through said support, and a series of chambers associated with the respective cylinders adapted to communicate successively with the aforesaid support port, pistons reciprocating in said cylinders, piston rods rigidly fixed to said pistons and reciprocating through glands at the inner ends of the cylinders, a pair of disks journaled in said support on an axis eccentric to the axis of the support, and link connections between the several piston rods cylinders and said disks.

In testimony whereof I have signed my name to this specification in the presence of two subscribing witnesses.
